R. H. BANNELL.
BALL DEBURRING MACHINE.
APPLICATION FILED NOV. 7, 1919.

1,395,789.

Patented Nov. 1, 1921.

Graventor:
Raymond H. Bannell
By Albert C. Tamm, Atty.

UNITED STATES PATENT OFFICE.

RAYMOND H. BANNELL, OF WATERBURY, CONNECTICUT.

BALL-DEBURRING MACHINE.

1,395,789.

Specification of Letters Patent.

Patented Nov. 1, 1921.

Application filed November 7, 1919. Serial No. 336,511.

To all whom it may concern:

Be it known that I, RAYMOND H. BANNELL, a citizen of the United States, and a resident of Waterbury, in the county of 5 New Haven and State of Connecticut, have invented certain new and useful Improvements in Ball-Deburring Machines, which improvements are fully set forth in the following specification.

10 This invention relates to improvements in constructions of that class available for automatically treating, for a deburring or rough-grinding effect, spheroidal objects, particularly when formed from metal and 15 usable as anti-friction bearing elements, such constructions being well-designated ball-deburring machines.

Machines of the general type available 20 for treating metallic spheroidal objects, as bearing balls and as herein contemplated, essentially comprise coöperating members capable of receiving between them and abrasively acting thereon, the spheroidal objects to be treated, such objects being successively 25 fed to and into the space intervening between said members and automatically delivered successively therefrom.

The object of this invention is to provide 30 a machine of the general character above indicated, which shall be simple and comparatively inexpensive as regards its construction; durable efficient and reliable in practical service; convenient in its application to practical purposes; and which shall 35 possess certain well-defined advantages over prior analogous constructions.

The invention consists in certain combinations, details and parts whereby, together 40 with the novel disposition and relative arrangement of said parts, the attainment of the foregoing object is rendered practicable, all of which will be hereinafter more specifically referred to and set forth in the claims hereto appended.

45 The invention is clearly illustrated in the accompanying drawing, wherein:

Figure 1 is a side elevation of a ball-deburring machine embodying my said improvements, and to more clearly disclose 50 details and parts thereof otherwise unduly obscured, a portion of the anterior deburring-member and of the anterior wall of the contemplated hopper, are broken away.

Fig. 2 is an end elevation of same, partly 55 in section, the section being taken diametri-

cally through the deburring-members of the machine, as along the dotted line $x-x$ of Fig. 1.

Fig. 3 is a top plan view of the contemplated hopper and parts more immediately 60 coöperating therewith, including the upper segments of the coöperating deburring-members.

Fig. 4 is a view showing in perspective and detached the duplex transfer-insert 65 which I make use of.

Having reference to the accompanying drawing, wherein similar reference-numbers denote like parts throughout the several views, I, in carrying out my present invention, make use of a posterior, (considered relatively to the upright position herein contemplated therefor), ball-deburring member 2, and, for coöperation therewith, an anterior ball-deburring member 2', said 75 members being, each in the general form of a flat ring having an operating face, and the coöperative relation thereof being such that a substantial abrasive effect may be had on any spheroidal object or objects positioned 80 at any time between them, in the practical operation of the machine.

However, it is herein contemplated that the posterior member 2 shall be duly supported fixedly, in any manner common and 85 well-known in the art, while the anterior member 2' shall rotate in close parallelism facewise therewith.

The operating face proper, as 2'', of the posterior member 2 is circumscribed by an 90 outer, marginal ledge 3, raised relatively thereto and duly interrupted at any appropriate segment thereof, preferably the top-most one, whereby duly spaced leading-on and leading-off terminals 3', 3'', respectively, are formed therefor, said member being further provided with an open ball-race 4, at and extending solely along the angle formed by and between the face 2'' and the inner wall of the ledge aforesigned 95 and conforming in cross-section to an arc of a circle whose convexity projects obliquely and outwardly downward.

The operating face proper, as 4', of the rotary, anterior member 2', circumscribes 105 an inner marginal ledge 4'', raised relatively thereto and uninterrupted, said anterior member being further provided with an open ball-race 5 at and extending solely along the angle formed by and between the 110

face 4' and the outer wall of the ledge last mentioned and conforming in cross-section to an arc of a circle whose convexity projects obliquely and inwardly upward, in 5 reverse opposition, accordingly to the ball-race 4, said ball-races varying in general diameter to this end, substantially as shown, and jointly forming, under the assembled condition of the members 2, 2', a complete, 10 practically closed ball-race non-circular in general cross-sectional contour, having its arc-intersecting diameter lying oblique to the plane of the assembled deburring members, and whose intake is at 5' and whose outlet 15 is at 5".

6 denotes a duplex transfer-insert positioned within the interrupted segment of the ledge 3, in this instance at the topmost portion of the posterior member 2, the same 20 being there displaceably held by means of any suitable fasteners, as the screws 6', 6". This transfer-insert projects radially inward to a point adjacent the outer wall of the ledge 4", and has its inner edge preferably 25 curved in conformity with a segment thereof, its opposite ends terminating duly short of the respective leading-on and leading-off terminals 3', 3", and being duly curved as shown for the formation with said terminals, respectively, of an initial ball-race section 7, constituting an intake continuation 30 of the closed ball-race aforesaid, and a final ball-race section 7', constituting a discharge continuation of said closed ball-race.

35 As will be noted, the prime function of the transfer-insert 6 is to insure the transference of the incoming objects to be treated from the interior of section 7, consecutively to and into the general, closed ball-race 40 aforesaid, situated between the members 2, 2', at the intake 5" thereof, and the transference consecutively from said general ball-race of any objects more or less treated and outcoming from the outlet 5" thereof, to and 45 into the section 7", for further onward delivery movement as may be found desirable in the practical operation of the machine, the function of said transfer-insert being, accordingly, two-fold.

50 Any appropriate supporting medium common and well known in the art may be availed of for co-operatively supporting the members 2, 2'.

I further purpose positioning duly above 55 the assembled deburring members of the machine, a charger 8, which may be of any desired general form and capacity, communication between the same and the ball-race section 7 being here shown as established by way of a suitable feed-pipe 60 8', and any spheroidal object contained within said charger escaping therefrom, each by its own gravity, and accordingly 65 entering the general ball-race aforesaid, primarily by way of said feed-pipe and

from thence by way of said section 7, as will be clearly understood.

At times it is desirable that the feeding of the objects undergoing treatment to and into the general ball-race aforesaid, shall 70 be continuous throughout a substantial period, or until duly interrupted by the operator of the machine; and to the attainment of this end, I provide a return take-off pipe 8", by way of which communication is established between the discharge end of the final ball-race section 7' and the interior of the charger 8, substantially as shown in the drawing forming a part hereof.

Where the take-off pipe 8" is employed 80 the objects undergoing deburring treatment within the general ball-race aforesaid will urge, each its neighbor next in advance thereof directly along said general ball-race, and from thence to and into said take-off pipe by way of the final ball-race section 7', said objects being accordingly returned, 85 through the medium of the take-off pipe 8", to and into the charger 8, from whence the objects again make their way, as hereinbefore explained, to and into the general ball-race aforesaid for further deburring treatment therein.

While the provision of co-operative elements whereby continuous feeding of the 95 objects undergoing treatment is secured, constitutes an important characteristic of my present invention, it is obvious that the same may be advantageously availed of where the take-off pipe aforesaid is omitted.

The various parts of the machine may be formed from any suitable material, and the operation thereof will be apparent from the foregoing description of same.

It will be seen that my improved ball-deburring machine is not only well adapted for the purposes for which it is intended, but that the same may be modified to a considerable extent, particularly as regards the specific form of the transfer-insert made use of, the medium employed whereby the objects treated within the general ball-race aforesaid are returned to and into the charger 8, and various minor details of the general construction, without departing from 110 the spirit and principle of my invention as coming within the scope of the claims here-to appended.

Having thus described my invention, I 115 claim:

1. A ball-deburring machine comprising 120 upright co-operative deburring members forming between them a general ball-race forming an elevated intake, one of said members having an interrupted segment; means 125 for feeding by gravity and by way of its elevated intake spheroidal objects to and into said ball-race for deburring treatment therein; and a transfer-insert, the latter occupying 130 said interrupted segment and affording

both an intake ball-race section and a delivery ball-race section, said intake and delivery sections constituting terminal continuations of said ball-race.

- 5 2. A ball-deburring machine comprising upright coöperative deburring members forming between them a general ball-race having an elevated intake, one of said members having an interrupted segment; means 10 for feeding by gravity and by way of its elevated intake spheroidal objects to and into said ball-race for deburring treatment therein; and a transfer-insert, the latter occupying said interrupted segment and forming a 15 ball-race section which constitutes a terminal continuation of said general ball-race.

3. A ball-deburring machine comprising upright coöperative deburring members forming between them a general ball-race 20 having an elevated intake and an elevated outlet; a charger, duly positioned above and in feed-communication with said general ball-race at the intake end thereof; and a

take-off pipe, the latter establishing communication between the charger aforesaid and said general ball-race at the delivery end thereof, and whereby objects treated within said ball-race are continuously returnable to and into said charger. 25

4. A ball-deburring machine comprising 30 upright coöperative deburring members forming between them having an elevated intake and an elevated outlet a general ball-race, one of said members having a segment interrupted for the formation of leading-on 35 and leading-off terminals, respectively, at the interrupted segment aforesaid; a transfer-insert occupying said interrupted segment, between said terminals, and forming with the latter, respectively, an intake 40 ball-race section and a delivery ball-race section; and means for duly feeding by gravity spheroidal objects to and into said ball-race by way of said intake section.

RAYMOND H. BANNELL.
